CLAIM

The ornamental design for a body fat meter, as shown and described.

DESCRIPTION

FIG. 1 is a perspective view of a body fat meter showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a top view thereof;

FIG. 8 is an end view thereof taken along line 8-8; and,

FIG. 9 is an end view thereof taken along line 9-9.

The broken lines in the drawings illustrate the portions of the body fat meter and form no part of the claimed design.
